United States Patent Office.

DAVID N. WILLIAMS, OF CHICAGO, ILLINOIS.

Letters Patent No. 63,125, dated March 19, 1867.

IMPROVEMENT IN APPARATUS FOR DRAWING IRON FROM THE FIRE.

The Schedule referred to in these Letters Patent and making part of the same.

TO ALL WHOM IT MAY CONCERN:

Be it known that I, DAVID N. WILLIAMS, of Chicago, Cook county, State of Illinois, have invented a new improved Apparatus for Drawing Iron from Furnaces; and I do hereby declare that the following is a full, clear, and exact description thereof, which will enable others skilled in the art to make and use the same, reference being had to the accompanying drawing, forming part of this specification, in which—

Figure 1 is a side view of my invention.

Figure 2, a plan or top view of the same.

Similar letters of reference indicate like parts.

This invention relates to a new and improved apparatus for facilitating the drawing of hot iron from furnaces, and has for its object the arranging or adapting of the several parts in such a manner that the tongs may be adjusted to draw the hot iron from the furnace in any required direction in a right line, thereby greatly facilitating the work, rendering it less laborious, and economizing in time.

A represents the mouth of the furnace through which the hot iron is drawn, and B is the platform or "standing" in front of the furnace on which the workmen stand. This platform or standing has a groove, a, made entirely through it in a direction parallel with the face or front of the oven. In this groove a I insert what I term a "traveller," the same consisting of a bar, C, having two pairs of rollers, b b', attached to it, the upper pair b resting on the top or upper surface of the platform or standing, and the lower rollers b' being at the under side, as shown clearly in fig. 1. To the upper end of the bar C there is pivoted a fork, D, in which a pulley, e, is fitted, and underneath which a chain, E, passes, one end of the chain being attached to a pair of tongs, F, and the opposite end attached to a sliding-drum, G, which is fitted on a tubular shaft, H, provided with a longitudinal feather, d, which is fitted in a groove in the drum, so that the latter may slide on shaft H and still be made to turn with the shaft. The shaft H is fitted loosely on a shaft, I, the bearings e of which are secured on parallel beams, f f, placed a suitable distance above the platform or "standing" B, and connected by cross-bars g, and the drum G is moved on the tubular shaft H by means of a lever, J, the upper end of which is connected by a bar, K, with an arm, L, the lower end of the latter being pivoted to a metallic strap, h, which encompasses loosely one end of the drum, and the upper end provided with a loop, i, fitted on a shaft, j, secured between the upper ends of two uprights, k k, attached to the cross-bars g g. The lower end of the lever J is within convenient reach of the workman on the platform or standing B, so that the drum may be readily shifted or moved on the tubular shaft H whenever required. The shaft H has a ratchet, l, at one end of it, into which a pawl, m, catches, and prevents the casual movement of H in the wrong direction; and said shaft H is connected with the shaft I, whenever required, by means of an ordinary clutch, M, actuated by a lever, N, which is also within convenient reach of the workman on the platform or "standing" B. The shaft I is rotated by a belt, O, from a driving-shaft, P, and this belt is kept at a proper degree of tension by means of a friction-roller or drum, Q, on the upper end of a lever, R, the latter being retained in position by catching into a rack-bar, S. By releasing this lever R from the rack-bar S the belt O may be loosened, so as to be inoperative or incapable of turning shaft I. The tongs F are composed of two arms or reins, n n, which cross each other, and are connected by a pivot, o, beyond which are the jaws p p. To one of the arms or reins n a guide-bar, q, is attached by a pivot, r, said bar being of curved form, and having its outer end passing through a slot in one of the jaws, (see fig. 1.) The chain E is connected to the tongs by having its end fitted to a swivel, s, attached to the outer end of a bail, t, which is secured to the tongs by the pivot o of the arms or reins.

From the above description it will be seen that by inserting the tongs into the mouth of the furnace, and grasping the "pile" or mass of hot iron, and then connecting the drum G with the tubular shaft H, and connecting the latter with shaft I by adjusting clutch M, the chain E will be wound upon drum G and the iron drawn from the furnace; and it will further be seen that by shifting the drum G on the tubular shaft H, the iron may be drawn from the furnace at right angles with the face or front thereof or in a more or less oblique direction in a right line, the traveller C admitting of this result. The guide-iron q facilitates the manipulation of the tongs' entrance into and withdrawal from the oven. The great advantage this invention possesses over others for a similar purpose is the perfect command allowed the operator over the tongs, its lateral adjustment obtained through the medium of the sliding-drum and traveller, to admit of the iron being withdrawn in differ-

ent directions as convenience may require, and the unobstructed platform or "standing" B, as well as the guide-iron *q* of the tongs. The shaft I may, if desired, be rotated by gearing instead of a belt.

Having thus described my invention, what I claim as new, and desire to secure by Letters Patent, is—

The sliding-drum G, in combination with the traveller C, chain E, and tongs F, all arranged to operate substantially in the manner as and for the purpose set forth.

DAVID N. WILLIAMS.
